[57] CLAIM

The ornamental design for a ductwork clamp, as shown and described.

DESCRIPTION

FIG. 1 is a perspective view of the ductwork clamp embodying the design of the present invention;
FIG. 2 is a front end elevational view thereof;
FIG. 3 is a rear end elevational view thereof;
FIG. 4 is a side elevational view thereof, the side opposite being a mirror image of the side shown in FIG. 4;
FIG. 5 is a top plan view thereof; and,
FIG. 6 is a bottom plan view thereof.

FIG. 1

FIG. 2

FIG. 3

FIG. 4

FIG. 5

FIG. 6
